Primary Examiner — Garth Rademaker*Assistant Examiner* — Melanie Pellegrini(74) *Attorney, Agent, or Firm* — Milord A. Keshishian(57) **CLAIM**

The ornamental design for a jewelry pendant, as shown and described.

DESCRIPTION

FIG. 1 is a front elevational view of a jewelry pendant showing our new design;

FIG. 2 is a rear elevational view thereof;

FIG. 3 is a perspective view thereof; and,

FIG. 4 is a front elevational view thereof, shown in an environment of use.

The broken lines showing a chain in FIG. 4 represent environment and also form no part of the claim. All other broken lines in the drawings illustrate portions of the jewelry pendant which form no part of the claimed design.
